UNITED STATES PATENT OFFICE.

JOHN YOCOM, OF DUNNVILLE, CANADA, ASSIGNOR OF ONE-HALF HIS RIGHT
TO LEVI MASSECAR, OF SAME PLACE.

IMPROVEMENT IN PLOWS.

Specification forming part of Letters Patent No. 158,561, dated January 5, 1875; application filed
October 26, 1874.

To all whom it may concern:

Be it known that I, JOHN YOCOM, of the Province of Ontario in the Dominion of Canada, have invented an Improvement in the Construction of a Plow, of which the following is a specification:

The object of my invention is the cheaper and more durable construction of plows, by the combination of a wrought-iron beam with a cast-iron plow-plate.

The following is a description of the construction of the same, reference being had to the annexed drawings.

In Figure 1, R represents the land-side plow-plate, having a groove, D S, into which the end of a wrought-iron beam, B, fits snugly, and is fastened in its place by means of bolts at the points m. There is also a groove, F M, along the bottom of the plate to receive the sole-plate and share, which are also fastened in their place by means of bolts. On top of the groove D S is a raised socket, K, to receive the cutter. On the back side of the plate, at the points I and L, are slight projections or

flanges, to which the mold-board C is bolted, and from the points S to E is another flange, under which part of the land-side handle G fits, and is made fast by a bolt at E. This handle is further secured to the land-side plow-plate by bolts at the points o. The whole of the above plate is cast in one piece.

Fig. 2 represents the whole plow when put together.

I claim as my invention—

1. The land-side plow-plate R, having the extension beam-piece H S, provided with a groove for the beam B, and a raised socket, K, for the cutter, all constructed as shown and described.

2. The combination of the plate R D S, beam B, mold-board C, point F, and land-side handle G, as constructed and operating as shown and described.

JOHN YOCOM.
